UNITED STATES PATENT OFFICE.

WILLIAM S. SCHROEDER, OF CHICAGO, ILLINOIS, ASSIGNOR OF ONE-HALF TO CHARLES H. FERRY, OF CHICAGO, ILLINOIS.

CAR-COUPING.

No. 858,762.

Specification of Letters Patent.

Patented July 2, 1907.

Application filed February 8, 1907. Serial No. 356,365.

To all whom it may concern:

Be it known that I, WILLIAM S. SCHROEDER, a citizen of the United States, residing in Chicago, in the county of Cook and State of Illinois, have invented a new and 5 useful Improvement in Car-Couplers, of which the following is a specification.

My invention relates to improvements in car couplers of the Master Car Builders' type, having the customary forked draw head and pivoted knuckle, and a vertically 10 movable gravity lock.

The object of my invention is to provide a car coupler of the Master Car Builders' type which will be of a simple, strong, efficient and durable construction, in which the vertically movable lock will itself have provision 15 for throwing the knuckle open and setting the lock in position for coupling and uncoupling, and in which the vertically movable lock will be operated from the side instead of from the top or above. A top lift lock, or one which is operated from above, is, in many cases, objectionable, owing to the danger of the lifting lever or its connection with the lock being torn off or broken, either by the draft rigging giving way or in loading material on flat or other cars, or owing to the lifting chain or connection being too long and dropping 20 down between the deadwood and the horn of the coupler.

My invention consists in the means I employ to practically accomplish the above mentioned object, as herein shown and described and more particularly specified 25 in the claims.

In the accompanying drawing, forming a part of this specification, Figure 1 is a longitudinal vertical section of a car coupler embodying my invention, showing the lock in position for holding the knuckle closed. Fig. 2 30 is a similar view showing the lock in its lock set position for uncoupling. Fig. 3 is a horizontal section on line 3—3 of Fig. 1. Fig. 4 is a vertical cross section on line 4—4 of Fig. 1, showing the lifting lever and its extension in elevation. Figs. 5 and 6 are views similar to 35 Figs. 1, 2 and 3, but illustrating the operation of the lifting lever and lock in throwing the knuckle open. Fig. 7 is a detail plan view. Fig. 8 is a detail side elevation of the lock. Fig. 9 is a detail front elevation of the lock. Fig. 10 is a detail perspective view of the 40 lifting lever.

In the drawing A represents the draw-head of the coupler, having the customary pivot arm a and guard arm a'; B the knuckle, having the customary front arm or nose b and rear arm or tail b'; C the pivot pin; D the 45 vertically movable side-lift lock fitting in the vertical aperture a² of the draw head; and F the side or laterally extending lifting lever, and F' the crank arm extension thereof. The draw-head A has a lock set seat

a³ in its lower web or floor a⁴ adjacent to the lock aperture a² therein. The rear arm or tail b' of the knuckle 55 is furnished with the customary hook or extension b², and with a flat upright face b³ to engage the lock. The rear arm or tail of the knuckle is also provided on its under side with an upwardly and laterally extending knuckle throwing incline b⁴, and preferably also with an upwardly and laterally extending incline b⁵ on its upper side, so that as the knuckle swings open this latter incline will lift the lock off the lock set seat of the draw head.

The lock D is provided at its lower end with a downwardly and forwardly projecting lock set leg or extension d, having a curved or cam-like upper face d¹ adapted to engage the knuckle throwing incline b⁴ on the rear arm or tail of the knuckle to throw the knuckle open. The vertically movable gravity lock D is provided on the knuckle side thereof with a recess d², having an upper curved or cam-like wall or face d³ for the bent lifting arm f of the lifting lever F to engage or slide and lift against, and having a lower wall or stop shoulder d⁴ which serves as a stop for the lifting arm of the 70 lifting lever F to engage when the lock is raised to its full extent, thus limiting the turning movement of the lifting lever. This shoulder d⁴ also acts as a stop to prevent creeping of the lock when the knuckle and lock are in their closed or coupled position by engagement with the lower end of the lifting arm f, as will be readily understood from Fig. 1 of the drawing. The recess d² also has an upright back wall d⁵.

The side or laterally extending lifting lever F extends horizontally through a side opening or bearing a⁵ 85 in the draw head above the knuckle tail, and the draw head is preferably provided with upright lugs a⁶ a⁶ between which the side lifting lever F fits. A removable pin G extends through one of these lugs a⁶ to hold the laterally extending lifting lever F in place. The side 90 opening a⁴ of the draw head for the lifting lever is preferably slightly elongated vertically, and the lifting lever is furnished with a rounded or curved heel f¹ to adapt it to be readily inserted and removed from the draw head when the pin G is removed. The horizontal 95 arm of the side lifting lever F is provided with a cam or eccentric f², to increase the throw of its lifting arm on the lock when the lever is turned and to complete the lifting of the lock to the required extent to throw the knuckle completely open.

The outer end of the side lifting lever F is provided with an eye f³ to engage the hook eye f⁴ of the lifting lever extension F', having the operating arm or crank f⁵, and which extends to the outside of the car. The crank arm extension F' of the lifting lever is loosely 105 supported by a bracket F⁶ secured to the front of the

car. The loose or knuckle-joint-like connection f^3 f^4 between the lifting lever F and its extension F^1 , enables the draw head of the coupler to move back and forth or up and down as required, without causing any 5 binding or stricture between the lifting lever and its extension.

The vertically movable, side-lift, gravity lock D is provided at its front corner with a shoulder d^6 which is adapted to ride or rest upon the rear arm or tail of the 10 knuckle when the knuckle is open or swinging open, and thus set or support the lock in position for coupling when the knuckle again closes.

The draw head A is preferably provided with an inclined projection a^7 , under which the lock set and 15 knuckle throwing leg or extension d of the lock fits when the lock is in its lowermost or closed position, which also aids in preventing the lock from creeping when the cars are coupled together. When the lock is lifted by the side lifting lever F the lower end of the lock 20 swings slightly backward at the initial upward movement to permit the knuckle throwing leg to clear this rearward projection a^7 of the draw head.

The operation is as follows: When the lock is lifted by turning of the lifting lever F, the lifting arm f thereof 25 engages the curved or cam-shaped lifting shoulder or upper wall d^8 of the recess d^2 near the front side thereof, and lifts the lock upward, the lower end of the lock at first moving slightly backward to clear the lock creeping prevention shoulder a^7 of the draw head, and 30 the further turning movement of the lifting lever throwing the lower end of the lock forward, so that the lock set toe or edge of the lock set leg d will overhang the lock set seat a^3 of the draw head, and thus positively insure the proper engagement of the lock with 35 the lock set seat of the draw head when the lock is permitted to again drop or descend by the operator releasing or letting go of the lifting lever F. When it is desired to throw the knuckle open by operation of the lifting lever and lock, the lifting lever is turned to the 40 full extent; in this operation the arm f of the lifting lever by its engagement with the curved lifting shoulder or cam d^3 on the lock, raises the lock until the knuckle throwing cam or incline d^4 on the lock engages the knuckle throwing cam or incline b^4 on the rear arm or 45 tail of the knuckle, and as the lock is further lifted throws the knuckle open; the operation of the lifting arm of the lifting lever on the curved lifting shoulder d^3 of the lock, also causes the lower end of the lock to move forward and follow the knuckle tail in its opening 50 movement as the lock is further raised. When the lock is at the lock set position, as shown in Fig. 2, when the knuckle swings open the incline b^4 on the rear arm or tail of the knuckle lifts the lock off the lock set and forces the lower end of the lock slightly backward 55 that the lock will properly clear the lock set seat a^3 of the draw head and drop certainly to position when the knuckle again closes in coupling. When the lock drops to the closed or coupled position it carries with it the inner arm f of the lifting lever, so that this arm 60 then hangs straight downwards, as shown in Fig. 1, and is thus in position by engagement of its lower end with the stop shoulder b^4 on the lock to prevent creeping of the lock and accidental uncoupling of the cars.

The lock D may preferably have an eye d^7 at its up-

per end so that it can be used as a top lift lock instead 65 of a side lift lock if occasion should require.

The lifting lever F is provided with a lip f^6 at its eye f^3 to engage the crank extension F^1 and prevent the latter from dropping down on the track in case its support F^2 should give way. 70

I claim:

1. In a car coupler, the combination with a forked draw-head having a lock aperture in its upper wall to receive and guide the lock and a lock set seat, of a knuckle having a knuckle throwing incline on its rear arm, and a vertically sliding gravity lock extending through the upper wall of the draw head and having at its lower end a downwardly and forwardly extending lock set and knuckle throwing leg, and provided at its side with a recess to receive and a lifting shoulder to engage the lifting arm of a lifting lever, and a side lifting lever extending horizontally through the side wall of the draw head and having a lifting arm fitting in said recess of the lock and 75 of the lock and engaging the lifting shoulder thereof, substantially as specified. 80

2. In a car coupler, the combination with a forked draw-head having a lock aperture and a lock set seat, of a knuckle having a knuckle throwing incline on its rear arm, and a vertically movable gravity lock having at its lower end a downwardly and forwardly extending lock set and knuckle throwing leg, and provided at its side with a recess to receive and a lifting shoulder to engage the lifting arm of a lifting lever, a side lifting lever extending horizontally through the side wall of the draw head and having a lifting arm fitting in said recess of the lock and 90 of the lock and engaging the lifting shoulder thereof, and said lock having also a stop shoulder at the lower end of said recess, substantially as specified. 95

3. In a car coupler, the combination with a forked draw-head having a lock aperture and a lock set seat, of a knuckle having a knuckle throwing incline on its rear arm, and a vertically movable gravity lock having at its lower end a downwardly and forwardly extending lock set and knuckle throwing leg, and provided at its side with a recess to receive and a lifting shoulder to engage the lifting arm of a lifting lever, a side lifting lever extending horizontally through the side wall of the draw head and having a lifting arm fitting in said recess of the lock and 100 of the lock and engaging the lifting shoulder thereof, the horizontal member of said side lifting lever being furnished with an eccentric to give an increased upward movement to the lock, substantially as specified. 105

4. In a car coupler, the combination with a forked draw-head having a lock aperture and a lock set seat, of a knuckle having a knuckle throwing incline on its rear arm, and a vertically movable gravity lock having at its lower end a downwardly and forwardly extending lock set and knuckle throwing leg, and provided at its side with a recess to receive and a lifting shoulder to engage the lifting arm of a lifting lever, a side lifting lever extending horizontally through the side wall of the draw head and having a lifting arm fitting in said recess of the lock and 115 and engaging the lifting shoulder thereof, and a crank arm extension of the lifting lever having a loose jointed connection therewith, substantially as specified. 120

5. In a car coupler, the combination with a forked draw-head having an opening in its upper wall to receive and guide the lock, of a knuckle having a knuckle throwing incline, a vertically sliding gravity lock extending through the upper wall of the draw head and having a knuckle throwing incline at its lower end, and provided with a recess to receive and a shoulder to engage the lifting arm of a side lifting lever, and a side lifting lever having a lifting arm fitting in said recess of the lock and 130 engaging the lifting shoulder thereof, substantially as specified. 135

6. In a car coupler, the combination with a forked draw-head, of a knuckle having throwing incline, a vertically movable gravity lock having a knuckle throwing incline at the lower end, and provided with a recess to receive and a shoulder to engage the lifting arm of a side lifting lever, and a side lifting lever having a lifting arm fitting 140

- in said recess of the lock and engaging the lifting shoulder thereof, said lifting shoulder of the lock being downwardly and forwardly inclined, and operating in conjunction with the lifting arm of the lifting lever to force the lower end of the lock forward as it is raised, substantially as specified.
7. In a car coupler, the combination with a forked draw-head, of a knuckle having a knuckle throwing incline, a vertically movable gravity lock having a knuckle throwing incline at its lower end, and furnished with a recess to receive and a shoulder to engage the lifting arm of a side lifting lever, a side lifting lever having a lifting arm fitting in said recess of the lock and engaging the lifting shoulder thereof, said lock having a stop shoulder at the lower end of the recess adapted to engage the lower end of the lifting arm to prevent creeping of the lock when the lock is closed, substantially as specified.
8. In a car coupler, the combination with a forked draw-head, of a knuckle having a knuckle throwing incline, a vertically movable gravity lock having a knuckle throwing incline at its lower end, and provided with a recess to receive and a shoulder to engage the lifting arm of a side lifting lever, a side lifting lever having a lifting arm fitting in said recess of the lock and engaging the lifting shoulder thereof, and a crank arm extension for the lifting lever, said lifting lever and its extension having loose interengaging eye connections with each other, substantially as specified.
9. In a car coupler, the combination with a forked draw-head, of a knuckle having a knuckle throwing incline, a vertically movable gravity lock having a knuckle throwing incline at the lower end, and provided with a recess to receive and a shoulder to engage the lifting arm of a side lifting lever, a side lifting lever having a lifting arm fitting in said recess of the lock and engaging the lifting shoulder thereof, said lifting shoulder of the lock being downwardly and forwardly inclined and operating in conjunction with the lifting arm of the lifting lever to force the lower end of the lock forward as it is raised, and a crank arm extension for the lifting lever, said lifting lever and its extension having loose interengaging eye connections with each other, substantially as specified.
10. In a car coupler, the combination with a forked draw-head, of a knuckle having a knuckle throwing incline, a vertically movable gravity lock having a knuckle throwing incline at its lower end, and furnished with a recess to receive and a shoulder to engage the lifting arm of a side lifting lever, a side lifting lever having a lifting arm fitting in said recess of the lock and engaging the lifting shoulder thereof, said lock having a stop shoulder at the lower end of the recess adapted to engage the lower end of the lifting arm to prevent creeping of the lock when the lock is closed, and a crank arm extension for the lifting lever, said lifting lever and its extension having loose interengaging eye connections with each other, substantially as specified.
11. In a car coupler, the combination with the draw-head having a lock aperture in its upper wall to receive and guide the lock therein and a lock set seat, of a knuckle and a vertically sliding gravity lock extending through the upper wall of the draw head and having a lock set leg at its lower end and provided with a recess to receive and a lifting shoulder to engage the lifting arm of a side lifting lever, and a side lifting lever having a lifting arm fitting in the recess of the lock and engaging the lifting shoulder thereof, substantially as specified.
12. In a car coupler, the combination with the draw-head having a lock aperture therein and a lock set seat, of a knuckle and a vertically movable lock having a lock set leg at its lower end and furnished with a recess to receive and a lifting shoulder to engage the lifting arm of a side lifting lever, and a side lifting lever having a lifting arm fitting in the recess of the lock and engaging the lifting shoulder thereof, said lifting shoulder of the lock being downwardly and forwardly inclined, substantially as specified.
13. In a car coupler, the combination with the draw-head having a lock aperture therein and a lock set seat, of a knuckle, and a vertically movable lock having a lock set leg at its lower end and provided with a recess to receive and a lifting shoulder to engage the lifting arm of a side lifting lever, and a side lifting lever having a lifting arm fitting in the recess of the lock and engaging the lifting shoulder thereof, said lock having a stop shoulder at the lower end of the recess adapted to engage the lower end of the lifting arm to prevent creeping of the lock when the lock is closed, substantially as specified.
14. In a car coupler, the combination with the draw-head having a lock aperture therein and a lock set seat, of a knuckle and a vertically movable lock having a lock set leg at its lower end and provided with a recess to receive and a lifting shoulder to engage the lifting arm of a side lifting lever, and a side lifting lever having a lifting arm fitting in the recess of the lock and engaging the lifting shoulder thereof, and a crank arm extension for the lifting lever having a loose eye connection therewith, substantially as specified.
15. In a car coupler, the combination with the draw-head having a lock aperture therein and a lock set seat, of a knuckle and a vertically movable lock having a lock set leg at its lower end and furnished with a recess to receive and a lifting shoulder to engage the lifting arm of a side lifting lever, and a side lifting lever having a lifting arm fitting in the recess of the lock and engaging the lifting shoulder thereof, said lifting shoulder of the lock being downwardly and forwardly inclined, operating in conjunction with the lifting arm of the lifting lever to force the lower end of the lock forward onto the lock set seat of the draw head when the lock is raised by the lifting lever, substantially as specified.
16. In a car coupler, the combination with the draw-head having a lock aperture therein and a lock set seat, of a knuckle and a vertically movable lock having a lock set leg at its lower end and provided with a recess to receive and a lifting shoulder to engage the lifting arm of a side lifting lever, and a side lifting lever having a lifting arm fitting in the recess of the lock and engaging the lifting shoulder thereof, said lock having also a stop shoulder at the lower end of said recess, substantially as specified.
17. In a car coupler, the combination with the draw-head having a lock aperture therein and a lock set seat, of a knuckle and a vertically movable lock having a lock set leg at its lower end and furnished with a recess to receive and a lifting shoulder to engage the lifting arm of a side lifting lever, and a side lifting lever having a lifting arm fitting in the recess of the lock and engaging the lifting shoulder thereof, said lifting shoulder of the lock being downwardly and forwardly inclined, and operating in conjunction with the lifting arm of the lifting lever to force the lower end of the lock forward onto the lock set seat of the draw-head when the lock is raised by the lifting lever, said lock having also a stop shoulder at the lower end of said recess, substantially as specified.
18. In a car coupler, the combination with the draw-head, of a knuckle, and a vertically movable lock furnished at one side with a recess therein having an upright back wall, a downwardly and forwardly extending upper wall, and a forwardly extending lower wall, and a side lifting lever fitting in a lateral opening in the draw head and having a lifting arm fitting in said recess of the lock and engaging the walls thereof to move and guide the lock in its upward and downward movements, substantially as specified.
19. In a car coupler, the combination with the draw-head, of a knuckle, and a vertically movable lock furnished at one side with a recess therein having an upright back wall, a downwardly and forwardly extending upper wall, and a forwardly extending lower wall, and a side lifting lever fitting in a lateral opening in the draw head and having a lifting arm fitting in said recess of the lock and engaging the walls thereof to move and guide the lock in the track in its upward and downward movements, said lock having at its lower end a lock set member, and said draw head having a lock set seat, substantially as specified.
20. In a car coupler, the combination with the draw-head, of a knuckle, and a vertically movable lock furnished at one side with a recess therein having an upright back

wall, a downwardly and forwardly extending upper wall, and a forwardly extending lower wall, and a side lifting lever fitting in a lateral opening in the draw head and having a lifting arm fitting in said recess of the lock and engaging the walls thereof to move and guide the lock in its upward and downward movements, said knuckle having a knuckle throwing incline, and said lock having at its lower end a knuckle throwing incline, substantially as specified.

21. In a car coupler, the combination with the draw head, of a knuckle, and a vertically movable lock furnished at one side with a recess therein having an upright back wall, a downwardly and forwardly extending upper wall, and a forwardly extending lower wall, and a side lifting lever fitting in a lateral opening in the draw head and having a lifting arm fitting in said recess of the lock and engaging the walls thereof to move and guide the lock in its upward and downward movements, said lock having at its lower end a lock set member and said draw bar having a lock set seat, said lock having also a lock set shoulder adapted to engage and rest upon the rear arm of the knuckle when the knuckle is open, substantially as specified.

22. In a car coupler, the combination with the draw head, of a knuckle, and a vertically movable lock furnished at one side with a recess therein having an upright back wall, a downwardly and forwardly extending upper wall, and a forwardly extending lower wall, and a side lifting lever fitting in a lateral opening in the draw head and having a lifting arm fitting in said recess of the lock and engaging the walls thereof to move and guide the lock in its upward and downward movements, said knuckle having a knuckle throwing incline, and said lock having at its lower end a knuckle throwing incline, said lock having also a lock set shoulder adapted to engage and rest upon the rear arm of the knuckle when the knuckle is open, substantially as specified.

23. In a car coupler, the combination with the draw head, of a knuckle, and a vertically movable lock furnished at one side with a recess therein having an upright back wall, a downwardly and forwardly extending upper wall, and a forwardly extending lower wall, and a side lifting lever fitting in a lateral opening in the draw head and having a lifting arm fitting in said recess of the lock and engaging the walls thereof to move and guide the lock in its

upward and downward movements, and an extension for 45 said side lifting lever having a loose eye connection therewith, substantially as specified.

24. In a car coupler, the combination with the draw head having an opening in its upper wall to receive and guide the lock, of a knuckle, a vertically sliding locking 50 pin extending through the upper wall of the draw head and a side lifting lever having a vertically swinging lifting arm, said locking pin having a lifting shoulder and a stop shoulder co-operating with said lifting lever, substantially as specified.

25. In a car coupler, the combination with a draw head having an opening in its upper wall to receive and guide the lock, of a knuckle, a vertically sliding locking pin extending through the upper wall of the draw head and a side lifting lever having a vertically swinging lifting 60 arm, said locking pin having a downwardly and forwardly inclined lifting shoulder, substantially as specified.

26. In a car coupler, the combination with a draw head, of a knuckle, a vertically movable locking pin and a side lifting lever having a vertically swinging lifting arm, 65 said locking pin having a downwardly and forwardly inclined lifting shoulder, and a stop shoulder, substantially as specified.

27. In a car coupler, the combination with a draw head, of a knuckle, a vertically movable locking pin and a side lifting lever having a vertically swinging lifting arm, 70 said locking pin having a lifting shoulder and a stop shoulder co-operating with said lifting lever, said lifting lever having an eccentric projection engaging the draw head, substantially as specified.

28. In a car coupler, the combination with a draw head, of a knuckle, a vertically movable lock, a side lifting lever having a lifting arm, and a horizontal member mounted in a lateral opening in the draw head and provided with an eccentric projection, said lock having a 80 side recess to receive the lifting lever, the back wall, upper wall and lower wall of said recess co-operating with the lifting lever to move and guide the lock up and down, substantially as specified.

WILLIAM S. SCHROEDER.
